UNITED STATES PATENT OFFICE.

EYVIND LEE HEIDENREICH, OF CHICAGO, ILLINOIS.

FIREPROOF ROOF, &c.

SPECIFICATION forming part of Letters Patent No. 689,081, dated December 17, 1901.

Application filed July 2, 1901. Serial No. 66,840. (No model.)

To all whom it may concern:

Be it known that I, EYVIND LEE HEIDENREICH, a resident of Chicago, in the county of Cook, State of Illinois, have invented certain new and useful Improvements in Fire-proof Roofs, &c., of which the following is a full, clear, and exact description.

This invention has for its object more particularly to provide an improved construction 10 of plate whereby roofs, ceilings, &c., may be formed; and the invention consists in the features of improvement hereinafter described, illustrated in the accompanying drawings, and more particularly pointed out in the claims 15 at the end of this specification.

Figure 1 is a view in vertical section through a roof embodying my invention. Fig. 2 is a view in cross-section on line 2 2 of Fig. 1. Fig. 3 is an enlarged detail view in cross-section, 20 showing the abutting ends of two roof-plates interlocked with a supporting-beam. Fig. 4 is a detail perspective view of one of my improved roof-plates. Fig. 5 is a view showing one edge of the improved roof-plate. Fig. 6 25 is an enlarged detail view showing the manner of connecting the sides of the roof-plates together. Fig. 7 is a detail view of one of the ridge-plates.

A designates the I-beams of the roof, which 30 may be arranged in usual or suitable manner. Across these I-beams extend channel-beams B, that are secured to the I-beams and are preferably U-shaped in cross-section, as shown. My improved construction of roof- 35 plate will rest upon the channel-beams and will be interlocked therewith, as will presently more fully appear. In the preferred form of the invention the plates that comprise the body of the roof are of substantially 40 the shape and construction shown in the drawings—that is to say, each of these plates C has one of its ends formed with a reverted edge c, adapted to engage the flange of one of the channel-beams B, as clearly shown in Figs. 1 45 and 3 of the drawings. This end of the plate C is preferably beveled, as at c', above the reverted end c, so as to receive the correspondingly-beveled end c² of the adjoining plate. Each of the main plates being thus 50 formed with a reverted end and with its opposite end beveled, the plates can be interlocked with the supporting-beams and can be

set together, as clearly shown in Figs. 1 and 3 of the drawings.

In order to enable the plates C to be securely joined or interlocked, each of these plates is formed with offset flanges c³ and c⁴ at one of its edges, these flanges c³ and c⁴ forming between them a channel adapted to receive the plane edge c⁵ of the next adjoining plate. (See Figs. 2 and 6.) The flange c³ upon the under side of each plate is cut away at its ends, as seen in Fig. 3, in order to permit the plates to be set in position upon the beams. Thus by reference to Fig. 3 it will be seen that in order to permit the reverted edge c to be hooked over the upper flange b of the channel-beam B the end of the plate-flange c³ must be first brought close to the back of the channel-beam and will then be drawn 70 away therefrom as the flange b of the beam engages the reverted end c of the plate. In placing the plates in position a layer of cement d will preferably be interposed between the flanges b of the channel-beams and the 75 engaging ends c of the plates. So, also, a layer of cement or mortar d' will be placed between the beveled portion c' of the plate and the correspondingly-beveled portion c² of the adjacent plate. A layer of cement or mortar d² 80 will also be placed in the joint between the flanges c³ and c⁴ of the plates and the edge c⁵ of the adjoining plates, that are received between these flanges. From this construction it will be seen that each of the roof-plates will 85 be securely locked to the cross-beams or channel-beams, and the plates of each row will have their side edges firmly locked together.

In Fig. 1 of the drawings is shown the preferred manner of forming the ridge of the 90 roof. This ridge will consist of angular ridge-plates E, each of which will be molded with the ribs e, adapted to fit over the transverse ribs c⁶, that will be formed adjacent the upper end of such of the plates C as will 95 be located immediately next to the ridge of the roof. At the ends the ridge-plates E will be formed with the flanges e² and e³, forming a channel to receive the edge of the adjoining ridge-plate, and each of the ridge-plates 100 will preferably be provided with a metal stay-frame consisting of intersecting wires, this stay-frame extending into one of the flanges at the end of the ridge-plate.

In practicing the invention the plates C will preferably be molded of mortar or like plastic material, and in the process of molding the plates there will be embedded in each 5 of the plates a metal stay-frame that consists, preferably, of transversely-disposed wires f and f' . By reference to Figs. 1 and 3 it will be seen that these wires are molded in the reverted ends c of each plate, thereby giving 10 great strength thereto and enabling the plate to securely engage the supporting channel-beam beneath it. It will also be seen that each of the metal stay-frames is extended into the beveled end c' of each plate, thereby 15 greatly enhancing the strength of such portion of the plate. The feature of forming plates from plastic material having stay-wires embedded therein is not novel; but I believe my present invention presents the first instance 20 of a plate formed from plastic material and having a reverted end, suitable metal stays being embedded in said plate and in said reverted end portion. The terms "reverted end" and "reverted edges" as herein 25 employed are not intended to limit the invention to the precise details set forth, since manifestly the extent to which the ends or edges are turned inwardly or reverted from the body of the plates is not essential. 30 One great advantage incident to the construction above described is that the plates being formed in section can be made at a distance from the work (and hence under cover and in any kind of weather) and can be 35 quickly set in place with but very little trouble and expense. A roof embodying this invention will be found particularly advantageous for factories, rolling-mills, steel-mills, and the like, where the gases incident to the 40 work being done would ordinarily tend to speedily destroy the corrugated-iron roofs commonly employed in such situations.

While the improved plates above described are more particularly intended for use in the 45 construction of roofs, it is manifest that such plates may also be advantageously used in forming ceilings, partitions, or like parts of fireproof structures. The ridge-plates E may be used for gutters and will be found 50 particularly applicable where gutters are interposed between the eaves of two adjoining roofs. In such case the ridge-plates E will simply be inverted. It will be readily understood that where special shapes are required 55 for conductors, gutters, &c., these may be easily molded and placed in position.

Having thus described my invention, what I claim as new, and desire to secure by Letters Patent, is—

60 1. A plate for roofs, &c., formed from plastic material and provided at one end with an angularly-extending or offset portion adapted to engage a supporting-beam and a metal frame or stay embedded in said plate and in 65 said angular or offset portion that engages said supporting-beam.

2. A plate for roofs, &c., formed from plas-

tic material and having a reverted edge, said plate having embedded therein a metal stay-frame extending around said reverted edge. 70

3. A plate for roofs, &c., formed from plastic material and having a reverted edge with a beveled upper surface. 75

4. A plate for roofs, &c., formed from plastic material having one edge reverted and beveled upon one side, the opposite end of said plate having its edge oppositely beveled. 80

5. A plate for roofs, &c., having one of its edges beveled and reverted and having its opposite edge beveled and metal stay extending around said reverted edge and into said opposite beveled edge. 85

6. A plate for roofs, &c., formed from plastic material and provided at one end with an angularly-extending or offset portion adapted to engage a supporting-beam and having its edges cut away to engage the edges of the adjoining roof-plates and a metal frame or stay embedded in said plate and in said angular or offset portion. 90

7. A fireproof structure comprising metal supporting-beams and bars and plates formed of plastic material having angularly-extending or offset portions adapted to engage said supporting-bars, said plates having their edges cut away to receive the edges of adjoining plates and metal stays or frames embedded in said plates and extending into their angular or offset portions and into their cut-away edges. 100

8. A roof for fireproof structures comprising metal supporting-beams and bars and plates of plastic material, said plates having their overlapping ends arranged opposite said supporting-bars and having angular or offset portions adapted to engage said supporting-bars, and metal frames or stays embedded in said plates and in their overlapping ends and angular portions. 105

9. A plate for roofs, &c., formed from plastic material having oppositely-offset flanges at one of its edges to form a channel to receive the edge of the adjoining plate, and metal stays embedded in said plate and extending into one of said offset flanges. 110

10. A plate for roofs, &c., formed from plastic material having one edge provided with offset flanges forming a channel at said edge to receive the edge of the adjoining plate, one of said edge flanges being shorter than the body of the plate to permit the interlocking of said reverted edge of the plate with the sustaining-beam. 120

11. A roof for fireproof structures, comprising metal beams and cross beams or bars and roof-plates formed of plastic material having inwardly-turned edges to interlock with said cross beams or bars, said plates being provided with suitable metal stays and the edges of the plates being interlocked together. 125
